JERMAIN P. BARNES, OF ROCHESTER, NEW YORK.

Design No. 4,665, dated February 21, 1871.

DESIGN FOR A HAND-STAMP FRAME.

The Schedule referred to in these Letters Patent and making part of the same.

To all whom it may concern:

Be it known that I, JERMAIN P. BARNES, of the city of Rochester, in the county of Monroe and State of New York, have invented and produced a certain new and original Design for the Frame of a Hand-Stamp, of which the following is a specification.

Nature of the Invention.

This design consists in the shape or configuration of the top of the frame in four star-points, as herein-after described; also, in the general shape and configuration of the legs and sides in connection therewith.

General Description.

The drawing represents a perspective view of my design.

A represents the top of the frame;
B B the sides; and
C C C the legs.

The top or bed of the frame is formed into four star-points, *a a a*, the apexes of which come at the four corners of the square, while the angles of the bases meet centrally at the sides of the same, and set inward of the plane of the square, as shown at *b b*.

This leaves rounded or convex sides *c c* to the star-points, which give a pleasing contour to the edges of the bed.

The top of the frame is surmounted by the ordinary socket *d*, for the reception of the handle or plunger.

The sides of the frame are formed with pendent points, *f f*, the apex downward, and the sides *g g* gradually curving backward till they meet the curves of the legs.

A line, *h*, extends from each apex to the central angles *b b*, and this line is inclined outward instead of standing vertically.

Rounded cheeks *k k* are formed each side of the line, which thus give a double swell to each side of the frame.

The legs are made in ogee-form, swelling outward, and at the bottom they have feet, *p p*, which give a firm base as well as present an ornamental appearance.

The ogees of the legs swell outward, as shown at *s s*, so as to give a broad support to the frame.

Claim.

What I claim, and desire to secure by Letters Patent, is—

The design for a hand-stamp frame, as herein set forth and shown.

J. P. BARNES.
